(57) **CLAIM**

The ornamental design for a device to lift a motion decoy, as shown and described.

DESCRIPTION

FIG. 1 is a perspective view of a device to lift a motion decoy, with the device shown in an extended position;
FIG. 2 is a front elevation view thereof;
FIG. 3 is a rear elevation view thereof;
FIG. 4 is a right side elevation view, with the left side being a mirror image thereof;
FIG. 5 is a top plan view of the device to lift a motion decoy;
FIG. 6 is a bottom plan view thereof;
FIG. 7 is an environmental perspective view of the device to lift a motion decoy, shown in a contracted position;
FIG. 8 is an environmental perspective view, shown in an extended position;
FIG. 9 is an environmental side elevation view, with the device shown in an extended position;
FIG. 10 is an environmental perspective view, shown in a contracted position; and,
FIG. 11 is an environmental perspective view of multiple devices to lift a motion decoy, shown in a contracted position.

The broken dash lines appearing in the drawings illustrate environmental structure and form no part of the claimed design. The dot-dash lines shown in the figures indicate that no particular length is claimed, and the area between the dot-dash lines forms no part of the claimed design.

1 Claim, 8 Drawing Sheets
